CLAIM

The ornamental design for a bead retention tray as shown and described.

DESCRIPTION

FIG. 1 is a front perspective view of a bead retention tray, showing our new design;

FIG. 2 is a rear view thereof;

FIG. 3 is a first side view thereof;

FIG. 4 is a second side view thereof;

FIG. 5 is a top, side perspective view thereof;

FIG. 6 is another top, side perspective view thereof; and,

FIG. 7 is a bottom view thereof.

The broken lines in the drawings depict portions of the bead retention tray that form no part of the claimed design.

1 Claim, 5 Drawing Sheets
